(57) **CLAIM**

(**) Term: **15 Years**

The ornamental design for a building scaffolding brace assembly, as shown and described.

(21) Appl. No.: **29/853,118**

DESCRIPTION

(22) Filed: **Sep. 13, 2022**

FIG. 1 is a perspective view of the building scaffolding brace assembly;

(51) **LOC (14) Cl.** **25-01**

FIG. 2 is a front view of the building scaffolding brace assembly of FIG. 1;

(52) **U.S. Cl.**

FIG. 3 is a rear view of the building scaffolding brace assembly of FIG. 1;

USPC **D25/126**

FIG. 4 is a right side view of the building scaffolding brace assembly of FIG. 1;

(58) **Field of Classification Search**

FIG. 5 is a left side view of the building scaffolding brace assembly of FIG. 1;

USPC D25/124, 68, 122, 35, 61, 126, 62, 66

FIG. 6 is a top view of the building scaffolding brace assembly of FIG. 1; and,

CPC .. E04G 7/32; E04G 13/02; E04G 1/06; E04B

FIG. 7 is a bottom view of the building scaffolding brace assembly of FIG. 1.

2001/246; E04C 3/32; E04C 3/30; E06C

The broken lines illustrate portions of the design that form

7/16

no part of the claim.
